UNITED STATES PATENT OFFICE

VIOLA RAFFAELLI, OF NEW YORK, N. Y., ASSIGNOR TO RAFFAELLI TRADING CO. INC.,
A CORPORATION OF NEW YORK

DESIGN FOR A CANDLESTICK OR ARTICLE OF ANALOGOUS NATURE

Application filed January 24, 1930. Serial No. 34,279. Term of patent 7 years.

To all whom it may concern:

Be it known that I, VIOLA RAFFAELLI, a citizen of the United States of America, and a resident of New York, county of Bronx, and State of New York, have invented a new, original, and ornamental Design for a Candlestick or Article of Analogous Nature, of which the following is a specification, reference being had to the accompanying drawing, forming a part hereof.

The single figure of the drawing shows a perspective view of the candlestick or article of analogous nature.

I claim:

The ornamental design for a candlestick or article of analogous nature substantially as shown.

VIOLA RAFFAELLI.
